(57) **CLAIM**

The ornamental design for a range hood, as shown and described.

DESCRIPTION

FIG. 1 is a perspective view of a range hood constructed in accordance with an embodiment of the present invention; FIG. 2 is a side view of the range hood shown in FIG. 1; FIG. 3 is a front view of the range hood shown in FIGS. 1 and 2; and,

FIG. 4 is a bottom view of the range hood shown in FIGS. 1–3.

The broken line showing of environmental structure is for illustrative purposes only and forms no part of the claimed design.
